UNITED STATES PATENT OFFICE.

WILLIAM FREDRICK SCHADEL, OF CHARLESTON, WEST VIRGINIA, ASSIGNOR TO KANAWHA MANUFACTURING COMPANY, OF CHARLESTON, WEST VIRGINIA, A CORPORATION OF WEST VIRGINIA.

CAR-DUMPING APPARATUS.

Application filed September 11, 1926. Serial No. 134,915.

- This invention relates to car dumping apparatus, an object of the invention being to provide improved mounting for a car receiving carriage whereby the carriage may be moved to a position to dump the car and return it to starting position through the medium of power operated means initiated manually, so that a single operator can control the entire mechanism.
- 10 A further object is to provide means for quickly and efficiently dumping the contents in the car, the entire operation being under control and the movement positive in both directions.
- 15 A further object is to provide an apparatus of this character in which the dumping operation requires no hand labor other than initiating the starting of the operation and which is comparatively simple in construction, not liable to get out of repair, and which will most efficiently perform the functions for which it is intended.

With these and other objects in view, the invention consists in certain novel features 25 of construction and combinations and arrangements of parts, which will be more fully hereinafter described and pointed out in the claims.

In the accompanying drawings—
30 Figure 1 is a plan view, illustrating my improved apparatus;

Figure 2 is a view in longitudinal vertical section on the line 2—2 of Figure 1;

Figure 3 is a view in transverse section on 35 the line 3—3 of Figure 2;

Figure 4 is a fragmentary view in longitudinal section on a scale larger than the views above described, showing the carriage in full lines in a position moving toward the 40 complete dumping position, said complete dumping position being indicated by a dotted line;

Figure 5 is a view in section on the staggered line of Figure 4;

45 Figure 6 is a fragmentary plan view on a scale larger than that shown in Figure 1, indicating the power transmitting mechanism;

Figure 7 is a fragmentary view in section 50 at right angles to Figure 6, the view being mainly on the line 7—7 of Figure 6;

Figure 8 is a view in section on the line 8—8 of Figure 6;

Figure 9 is a fragmentary view in section on the line 9—9 of Figure 6.

A represents my supporting frame, B a movable carriage on the frame A, and C a car adapted to be run onto and off the carriage, all of which will be more fully hereinafter described.

The frame A of structural steel is of general rectangular form and is adapted to rest upon the ground, or upon a support, in such position as desired. I have indicated the frame as supported so as to allow the car to be dumped over the edge of a hill, particular reference being made to Figures 2 and 4, but it is to be understood that the frame may be located at any point where the dumping operation is desired.

The carriage B is of general oblong shape, positioned transversely of the support A and having a pair of wheels 1 and 2 at each end. The wheels 1 are adapted to run upon rails 3, and the wheels 2 are adapted to run upon rails 4.

These rails 3 and 4 curve upwardly from the plane of the normal or initial position of the carriage, and terminate at their extremities in the form of hooks 5 and 6, respectively, the hook 6 being in a plane appreciably above the hook 5 and spaced from the hook 5 the distance between the wheels 1 and 2.

Furthermore, it will be noted by reference to Figures 2 and 4, that the hook 6 projects in a plane beyond the hook 5 so that when the carriage is moved to the extremity of the tracks or rails the latter will be moved to any angle past the vertical plane or past the perpendicular so that the entire contents of the car C supported on the carriage will be dumped.

The carriage B is made with a pair of rails 7, constituting a track which registers with the service track 8, indicated by dotted lines in Figure 1, so that the car C may be run from the service track directly on to the tracks of the carriage until the wheels 9 of the car engage stop blocks 10 on the carriage to limit the further movement of the car and center the car on the carriage.

To prevent accidental retrograde movement of the car I provide blocks 11 fixed to a shaft 12 mounted in the carriage, and these blocks 11 move upwardly when per-

mitted and hold the car against movement. The shaft 12 is formed with short crank arms 13 connected by springs 14 with fixed bars 15' on the carriage so that these springs 5 normally tend to hold the free ends of the blocks 11 in elevated position against wheels 9 of the car C. On the shaft 12 a hand lever 15 is provided, which is manually operated to depress the blocks 11 when it is desired 10 to move the car off of the carriage.

The upper edges of the blocks 11 are inclined, as shown at 16, so that the wheels 9 of the car C will depress the blocks as they ride over the same in their movement on to 15 the carriage, but when the forward pair of wheels engages the blocks 10 the blocks 11 will spring upwardly against the other pair of wheels and confine the wheels between said blocks 10 and 11 so that there can be 20 no accidental movement of the wheels on the rails 7.

To prevent any possibility of the car's displacement from the carriage during the dumping operation, I secure angle brackets 25 17 to the under face of the car body 18 and these angle brackets ride under angle bars 19 on supports 20 which are fixed to the carriage, as clearly indicated in Figures 2 and 4. In other words, these angle bars 19 30 constitute rails and the angle brackets 17 move under the rails so that they prevent any possibility of the wheels 9 of the car C from leaving the rails 7.

The supporting frame A at its dumping 35 end and at both sides thereon is provided with two pairs of shafts 21 and 22. These shafts carry sprocket wheels 23 and 24, respectively. At the other end of the supporting frame A similar pairs of sprocket 40 wheels 25 and 26 are located. Sprocket wheels 25 are mounted on shafts 27 and sprocket wheels 26 are secured to a shaft 28 which is common to both of the sprocket wheels and extends throughout substantially 45 the transverse dimension of the supporting frame A at one end, as clearly indicated in Figures 1 and 6.

29 represents an axle which is mounted on wheels 30. The latter are movable in 50 channel rails 31 secured to the frame A. The axle 29 supports a pair of sleeves 32 having lugs 33 and 34 at opposite sides thereof. Each lug 33 is adjustably connected to one end of the chain 35, and the other 55 lugs 34 are connected to the opposite ends of the same chain 35. As clearly indicated, there are two of these chains 35 and the chains extend from the lugs 34 longitudinally of the support A, thence under the 60 sprocket wheels 24, thence around the sprocket wheels 23, thence longitudinally of the frame A, around sprocket wheels 26, under sprocket wheels 25, and are secured to the lugs 34. Hence, when movement is 65 imparted to the chains through the medium

of the shaft 28 the axle 29 is caused to move longitudinally of the supporting frame, the wheels 30 moving along the channel rails 31 and held against vertical movement by reason of said channel rails.

A shaft 36 is mounted on the bottom of the carriage B, and collars 37 on said shaft 36 are connected by links 38 with collars 39 on axle 29, so that when the axle is caused to move the carriage is also moved, 75 as will be readily understood.

I preferably provide rollers 40 on the shaft 36 where said shaft will engage the runs of the chains 35 to prevent undue wear and reduce friction to a minimum.

I would call particular attention to the mechanism for transmitting motion to the shaft 28, and refer particularly to Figures 6, 7, 8 and 9 of the drawing. 41 indicates a motor, which is preferably an electric 85 motor, on the shaft 42 of which I secure a sprocket wheel 43 which is connected by a chain 44 with a sprocket wheel 45 on a shaft 46, said shafts being suitably mounted on the supporting frame A.

The shaft 46 carries a bevel pinion 47 which is always in mesh with a pair of bevel gears 48 and 49, respectively, and these gear wheels 48 and 49 are loose on a shaft 50 which is secured on frame A parallel to the 95 shaft 28.

51 and 52 represent clutches keyed to slide on the shaft 50. To these clutches arms 53 are operatively connected, and said arms 53 form fixed parts of blocks 54 mounted to 100 slide upon a shaft 55. The shaft 55 has a pinion 56 secured thereon, which meshes with a gear wheel 57 on shaft 28, and said gear wheel 57 is driven by a pinion 59 secured to shaft 50.

To initiate the starting movement of the apparatus I employ preferably a hand lever 60 pivotally connected to support A and having a rod 61 connected thereto. This rod 61 projects through the blocks 54 and 110 has adjustable stops 62 and 63. A second rod 64 extends through the blocks 54 and carries adjustable stops 65 and 66 thereon. These stops 62 and 63 and 65 and 66 are preferably collars which are loose on the rods and fixed thereto in any approved manner. I have indicated pins or screws for the purpose.

The shaft 55 throughout the intermediate portion of its length is screw threaded and a nut 67 is mounted on this threaded portion of the shaft 55, and the rod 64 is projected through an opening in the nut so that the nut is held against turning movement but is free to move longitudinally of the shaft 55 125 when the latter is revolved.

The operation of this driving mechanism, indicated in Figures 1 and 6 of the drawing, is as follows: The parts are shown in a neutral position. To start the operation the 130

lever 60 is moved to cause the rod 61 to move longitudinally and the stop 62 will force the block 54 and the clutch 51 in a direction to lock the clutch 51 and gear wheel 48 together. Then motion will be transmitted from the pinion 47 to the gear wheel 48 to turn the shaft 50. Motion will be transmitted from shaft 50 through the medium of the gear wheels 59, 57 and 56 to turn the shafts 28 and 55. The turning of the shaft 50 causes a movement of the chains 35 to move the carriage and the car to a dumping position, as above explained, and during this movement the turning of the shaft 55 will cause the nut 67 to move longitudinally of the shaft until it engages the stop 65. This stop 65 will be against the face of block 54 when clutch 51 is in engagement with the gear wheel 48, so that as the nut 67 engages the stop 65 it will force the block 54 in a direction to move the clutch 51 away from its engagement with the gear wheel 48 and stop the movement of the carriage as the latter reaches its full dumping position. When the load is completely dumped, the operator moves the lever 15 in the direction opposite to the first defined movement to draw the stop 63 against the block 54 and move the clutch 52 into engagement with the gear wheel 49. The shaft 28 will then be turned in the direction opposite to that above described until it comes into contact with the stop 66 against block 54 and will force the clutch 52 away from gear wheel 49 and stop the transmission of motion to the carriage. It will thus be noted that a single operator controlling the movement of lever 60 can initiate the movement of the carriage in both directions and that when said motion or movement is initiated, the movement will be completed and automatically stopped without any further attention of the operator. Thus a car can be loaded on to the carriage and quickly and efficiently dumped, requiring no labor in the operation other than the movement of the car on the carriage and the initiation of movement by the operation of the lever 60.

While I have illustrated what I believe to be a preferred embodiment of my invention it is obvious that various changes and alterations might be made in the general form of the parts described without departing from the spirit of the invention, and hence I do not limit myself to the precise details set forth but consider myself at liberty to make such slight changes and alterations as fairly fall within the spirit and scope of the appended claims.

I claim:

1. A car dumping apparatus, including a supporting frame, a four wheeled carriage movable on the frame, two pairs of tracks on the frame receiving the front and rear wheels respectively of the carriage and guid-

ing the carriage to dumping position, and rails on the carriage adapted to register with service rails to receive the car on the carriage, said first-mentioned pairs of tracks extending upwardly at one end, the tracks for the rear wheels of the carriage being at the dumping end of the support in a higher plane than the other tracks, and said pairs of tracks at their free ends constituting hooks to receive the wheels of the carriage and hold the carriage in dumping position. 70 75

2. A car dumping apparatus, including a supporting frame, a wheeled carriage movable on the frame, tracks on the frame receiving the wheels of the carriage and guiding the carriage to dumping position, and rails on the carriage adapted to register with service rails to receive the car on the carriage, said first-mentioned tracks extending upwardly at one end, the tracks for the rear wheels of the carriage being at the dumping end of the supporting frame in a higher plane than the other tracks, and said tracks at their free ends constituting hooks to receive the wheels of the carriage, the hooks of the upper tracks 80 85 90 projecting beyond the plane of the hooks of the lower track.

3. A car dumping apparatus, including a supporting frame, a wheeled carriage movable on the frame, tracks on the frame receiving the wheels of the carriage and guiding the carriage to dumping position, rails on the carriage adapted to register with service rails to receive the car on the carriage, said first-mentioned tracks extending upwardly at one end, the tracks for the rear wheels of the carriage being at the dumping end of the support in a higher plane than the other tracks, and said tracks at their free ends constituting hooks to receive the 95 100 105 wheels of the carriage, supports on the carriage, angle bars on the supports, and angle brackets on the car adapted to engage under said angle bars and hold the car against tilting movement on the carriage. 110

4. A car dumping apparatus, including a supporting frame, a wheeled carriage movable on the frame, tracks on the frame receiving the wheels of the carriage and guiding the carriage to dumping position, rails 115 to receive the car on the carriage, said first-mentioned tracks extending upwardly at one end, the tracks for the rear wheels of the carriage being at the dumping end of the supporting frame in a higher plane than the other tracks, and said tracks at their free ends constituting hooks to receive the 120 125 wheels of the carriage, the hooks of the upper tracks projecting beyond the plane of the hooks of the lower tracks, supports on the carriage, angle bars on the supports, and angle brackets on the car adapted to engage under said angle bars and hold the car against tilting movement on the carriage.

WILLIAM FREDRICK SCHADEL.
